(57) **CLAIM**

The ornamental design for a portion of a bracelet, as shown and described.

DESCRIPTION

FIG. 1 is a top perspective view of a first embodiment of a portion of a bracelet showing our new design;
FIG. 2 is a right side elevation view thereof;
FIG. 3 is a left side elevation view thereof;
FIG. 4 is a front elevation view thereof;
FIG. 5 is a rear elevation view thereof;
FIG. 6 is a top plan view thereof;
FIG. 7 is a bottom plan view thereof;
FIG. 8 is a bottom perspective view thereof;
FIG. 9 is a top perspective view of a second embodiment of a portion of a bracelet showing our new design;
FIG. 10 is a right side elevation view thereof;
FIG. 11 is a left side elevation view thereof;
FIG. 12 is a front elevation view thereof;
FIG. 13 is a rear elevation view thereof;
FIG. 14 is a top plan view thereof;
FIG. 15 is a bottom plan view thereof; and,
FIG. 16 is a bottom perspective view thereof.

The broken lines shown in FIGS. 1 through 16 represent environmental subject matter only and form no part of the claimed design.

1 Claim, 12 Drawing Sheets
